UNITED STATES PATENT OFFICE.

HERMAN F. A. BORNEMAN AND JACOB DAAB, OF COLUMBUS, OHIO.

SPIRAL STAIRWAY.

SPECIFICATION forming part of Letters Patent No. 485,449, dated November 1, 1892.

Application filed April 2, 1892. Serial No. 427,431. (No model.)

To all whom it may concern:

Be it known that we, HERMAN F. A. BORNEMAN and JACOB DAAB, citizens of the United States, residing at Columbus, in the county of 5 Franklin and State of Ohio, have invented a certain new and useful Improvement in Spiral Stairways, of which the following is a specification.

Our invention relates to the improvement 10 of spiral or winding stairways; and the objects of our invention are to provide a winding or spiral stairway of superior construction, to construct the same in a neat, strong, and durable manner, to provide improved means for 15 supporting the steps from a common standard, to provide improved means for connecting the banister-rail and newel-posts, and to produce other improvements, which will be more specifically pointed out hereinafter. 20 These objects we accomplish in the manner illustrated in the accompanying drawings, in which—

Figure 1 is a view in elevation of our improved stairway. Fig. 2 is a central vertical 25 section of a portion of the central supporting-tube. Fig. 3 is a central sectional view of a portion of one of the newel-posts, showing the manner of connecting therewith the banister-rail. Fig. 4 is a central sectional view of 30 the lower portion of the central supporting-tube and its supporting base-plate. Fig. 5 is a detail view in perspective of the inner end portion of one of the vertical step portions. Fig. 6 is an enlarged sectional view taken on 35 line xx of Fig. 1 and being a central sectional view through one of the vertical step portions and a portion of the central supporting-tube, and Fig. 7 is a transverse section of the two step portions.

Similar letters refer to similar parts throughout the several views.

In forming our improved stairway we employ, as shown, a central vertical supporting-standard a in the form of a tube. The lower 45 end of this standard is supported, as shown, within a suitable socket b , formed in the upper side of a base-plate b' , the latter being adapted to be secured to the floor of a building.

c represents the vertical step portions, and c' the horizontal step top portions, to the under side of which, near their forward edges,

are secured the upper edges of the portions c . As is usual in this class of stairways, the top boards c' of the steps gradually widen as they 55 extend outwardly from the central support. The inner end of each of the step portions c is provided, as shown at c^2 , with a plate or casting which is, substantially, in the form of an inverted L , the upper arm of said casting 60 being secured to and flush with the upper side of the step portion c . The vertical arm of the casting c^2 extends, as shown, against the inner end of said step portion and is secured thereto by suitable screws c^3 . This 65 vertical arm or end facing of the step portion c is provided with two outwardly-projecting studs d , the latter having enlarged heads, as indicated.

The central tubular support a is provided, 70 as shown, with as many pairs of openings e in its periphery as there are vertical step portions c , the openings of each pair being arranged one vertically beneath the other, and said pairs being arranged spirally in said 75 tube, as indicated in Fig. 2 of the drawings. Each of the openings e is of the usual key-hole form—*i. e.*, consisting of a circular upper end, from which extends vertically downward a neck, (indicated at e^3). The inner end 80 of each of the step portions c is connected with the tubular standard a by inserting the heads of the casting-studs d through the larger ends of the openings e and dropping said step portion downward until the stems 85 of said studs are in the portions e^3 of said openings. In this manner it will be seen that the step portions c are prevented by the bearing of the heads of the studs d against the inner side of the tube from dropping downward 90 or becoming loosened therefrom. The inner end of each of the top plates c' of the steps is concaved to conform to the curve of the periphery of the central standard against which said top plate abuts. 95

f represents the side stringer or side beam of our improved stairway, which is of the spiral form shown. This side beam consists of an inner vertical layer of wood f' , on the outer side of which is secured a similar wood 100 layer f^2 .

f^3 represents metallic plates or strips which extend throughout the length of said side beam, said plates being arranged at a dis-

tance, one above the other, in properly-shaped depressions formed in the outer face of the wood layer f^2 . These metal plates are by means of suitable screws or bolts, which are indicated at g , secured to the wood layer f' and to the end of the step portions c , as indicated in Fig. 6 of the drawings. On the outer side of the wood layer f^2 is secured an outer layer, preferably of wood, (indicated at g')

5 g^2 represents suitable beads which are secured to the face of the outer layer g' , preferably adjoining the upper and lower sides thereof. Rising from the upper side of the beam f are suitable banisters k , the upper ends of which are connected by a suitable banister-rail k' . The upper and lower ends of this rail k' are secured, as hereinafter described, to the upper portions of newel-posts m , while the side beam f is secured to the 15 bases of said posts.

10 As indicated in Fig. 3 of the drawings, we provide in the upper portion of each of the newel-posts a socket or depression p , the mouth of which is partially closed by a plate p' , having a central slotted opening p^2 . To the inner side of the upper portion of the plate p' we secure, as shown, the upper end of a downwardly-extending spring-strip p^3 , which extends to about the center of the height of the 15 slotted opening p^2 . At each end of the banister-rail we provide a hook extension p^4 , which is adapted to enter the slotted opening p^2 of the plate p' and engage with said plate, as shown. In thus effecting a connection between the banister-rail and newel-posts it will be seen that the lower end of the spring p^3 will by contact with the upper side of the hook p^4 operate to prevent such elevation of said banister-rail as may serve to admit of its withdrawal from the socket. In case it is desired, 20 however, to separate the rail and post a slight inward pressure upon the spring p^3 by any desired tool inserted through the upper portion of the slot p^2 will result in the disengagement of said spring with the hook of the ban-

ister-rail and admit of the latter being elevated and withdrawn. It is obvious that the upper newel-post may be supported upon the flooring or in any well-known or desired manner.

50

From the construction herein shown and described it will be seen that a novel and reliable construction of a spiral stairway is provided, which will be exceedingly strong and durable and which may be produced in a neat and substantial manner at a reasonable cost of manufacture.

55

Having now fully described our invention, what we claim, and desire to secure by Letters Patent, is—

60

1. In a winding or spiral stairway, the combination, with the central tubular standard and the slotted openings e therein, of the step portions having projecting studs d adapted to engage with said openings e , top step-plates c' , and side beam, substantially as and for the purpose specified.

65

2. In a winding or spiral stairway, the combination of the central tubular standard a , keyhole-shaped openings e , arranged spirally therein, step portions c , and studs d , projecting from the ends thereof and having enlarged heads, said studs adapted to engage, as described, with said slotted openings e , substantially as and for the purpose specified.

70

3. In a spiral or winding stairway, the combination of the central tubular standard a , openings e therein, step portions c and c' , studs d , projecting through said portions c and adapted to engage, as described, within said openings e , and spiral side beam f , consisting of two or more connected wood layers and intervening metallic plates f^3 , the latter being secured to the steps, substantially as and for the purpose specified.

75

HERMAN F. A. BORNEMAN.
JACOB DAAB.
